N. Y., A CORPORATION OF NEW YORK

SANITARY BOWL WITH HYDRAULIC DRIER

Application filed October 9, 1930. Serial No. 487,410.

This invention relates to improvements in water closets, bidets and similar appliances of the type where the cleansing operation is performed by means of a jet of water, followed by a drying jet of air. More particularly the invention refers to improvements in methods of and apparatus for supplying to the nozzle air under pressure, in order to perform the drying operation.

10 An attachment for water closets or bidets making it possible to direct a jet of water against the body of the user for cleansing purposes, has been described and claimed in a patent application, entitled, Sanitary attachment for water closets, Ser. No. 455,554, copending herewith. The device to which

15 said application refers also comprises a front-wardly directed air discharge outlet at the rear and a rotary fan supplying the air thereto.

20 In another copending application, entitled Methods of and apparatus for sanitary cleansing, Ser. No. 283,234, we have described and claimed improvements in a method and apparatus for directing a jet of water and a jet of air against the spot to be cleansed and dried, said improvements being particularly directed to the fact that both jets are made to issue from a nozzle in close proximity of the surface to be cleaned, and so that they will reach the proper spot at a velocity sufficient to insure thorough, effective and rapid action.

25 In addition to these remarks, it is also to be noted that in a great many localities, electric power is not as yet available, so that the use of the apparatus shown and described in application for method of and apparatus for sanitary cleansing, Ser. No. 483,234, would 30 be out of the question in such places. On the other hand, water is always available practically all over the world at pressures sufficient to permit its potential energy to be used in supplying air to the nozzle of the apparatus at the desired pressure.

Accordingly, the primary object of this invention is to provide a novel and improved method of supplying air under pressure to an apparatus of the class specified, whereby the necessary pressure is obtained by utilizing

the pressure of the water obtainable from the same source of supply which is used for flushing the toilet or bidet.

Another object is to provide in apparatus of the class specified, a novel and improved arrangement for operating the apparatus entirely by means of the water supply to which the apparatus may be connected.

55 A further object is to provide a sanitary appliance to be used in connection with or forming part of a water closet or bidet, permitting of directly transforming the pressure of the water available from the water supply into pressure of air issuing as a drying jet from a nozzle forming part of the apparatus.

60 A still further object is to provide in a water closet or bidet, equipped with means for effecting a body cleansing operation by means of a jet of liquid directed against the exposed parts of the body of the user requiring it, means for supplying air to a properly located nozzle under a positive pressure sufficient to insure a quick and effective drying action, said pressure being obtained by the 65 direct and substantially noiseless utilization of the pressure available in the water supply.

70 Other objects and advantages of the present invention will more fully appear as the description proceeds and will be set forth 75 and claimed in the appended claims.

Our invention is illustrated by way of example, in the accompanying drawings, in which:—

75 Fig. 1 is a plan view of a water closet bowl associated with a cleansing and drying apparatus embodying our invention;

80 Fig. 2 is a front view in elevation partly sectioned of the same;

85 Fig. 3 is a vertical cross section of the upper part of the stand carrying the controls and the nozzle of the cleansing and drying apparatus;

90 Fig. 4 is a side sectional view of one of the chambers of the water operated air pump;

95 Fig. 5 is a side sectional view of the other chamber of said pump;

100 Fig. 6 is a fragmentary side view in elevation of the stand showing the controlling valve;

Fig. 7 is a cross sectional view of the controlling valve shown in Fig. 6; and

Fig. 8 is a fragmentary longitudinal section of the tip end of the preferred form of nozzle used in connection with our invention.

5 The jet of water used for the cleansing operation proper should preferably be directed at a slant so as to avoid splashing and so that it will at the same time actually carry away particles of foreign matter adhering to the spot to be cleaned by impact or mechanical action.

10 In order to obtain an efficient drying action, a jet of air, preferably heated, should also be sent against the spot to be dried under a positive and material pressure from a point of issue relatively close to said spot. The air thus delivered should also preferably be at a slant to the surface to be dried so that as a result of these various conditions, the air will be supplied in a volume sufficient to induce quick evaporation and also at a relatively high velocity causing said air to blow off liquid particles adhering to the wet surface, thus materially decreasing the time required for drying it.

15 For the purpose of our invention it is preferable that both the water and air supplied to the nozzle or nozzles be heated, although this is not a necessary condition, the use of 20 the heating facilities provided being entirely, if desired, under the control of the user.

25 Referring to the drawings, 10 designates a toilet bowl of usual construction comprising a base 11 and a rim 12 formed with a passage 13, through which water flows from a suitable source of supply in order to flush the bowl in the customary manner. The bowl is provided with a seat 14 on top which 30 is hinged at 15 to the rear of the bowl; the lower surface 16 of the seat is usually provided with rubber spacing heads 17 resting upon the top of rim 12 causing a clearance 18 to remain between the top of the bowl and 35 the lower surface of the seat.

40 The cleansing and drying device proper preferably comprises a stand 19, having a base 20 adapted to be placed upon the floor alongside the toilet bowl. At the upper end 45 of said stand is mounted a head 21, carrying all the operating and controlling parts, the bottom part 22 of said head forming with a cavity 23 at the upper end of stand 20, a chamber to which water under pressure may 50 be admitted through pipe 24. The portion of said stand underneath chamber 23 is hollow, forming an air chamber 25 connected by an opening 26 at the tip to a passage or chamber 27, within which projects an electric heating 55 element 28, adapted to heat the air on its way from the chamber 25 to the nozzle through delivery passage 29 at the upper end of the stand and delivery passage 30 registering therewith, provided in head 21.

60 The bottom 31 of water chamber 23 is pref-

erably made of light gauge sheet metal and is relatively close to heating element 28, so that when said heating element is energized, the heat produced thereby will be sufficient to raise the temperature of the water contained in or passing through the water chamber.

65 A nozzle supporting member 32 operable by means of a handle 33 is rotatably mounted on head 21 so as to be angularly movable about a vertical axis. Said supporting member is carried by a tubular shaft 34 which is formed integral with an outer shell portion 35 forming an annular chamber 36 surrounding said hollow shaft. The lower surface 37 of shell 35 forms a seat determining the depth at which the shaft and shell can be inserted within head 22 and the lower end of hollow shaft 34 is threaded as shown at 38, to receive nut 39, restraining shaft 34 against axial displacement while permitting angular movement thereof. Hollow shaft 34 forms a tubular passage 40 leading from cavity or chamber 23 to another chamber 41 within supporting member 32. Air passage 30 leads to a chamber 42, surrounding a tract of shell portion 35 which is provided in correspondence of said chamber with circumferential openings such as 43 through which air may be admitted to annular chamber 36.

70 Supporting member 32 carries a fluid delivery arm 44, which terminates in a nozzle portion 45. In its preferred form the fluid delivery arm comprises an inner tubular member 46 forming an outlet for chamber 41 and an outer tubular member 47 forming with tubular member 46 an annular chamber 48 constituting an outlet for a chamber 49, to which leads the upper end of shell portion 35. Said two tubular members 46, 47 together form the fluid delivery arm. Said delivery arm preferably comprises a horizontal tract 50 which is flattened so as to permit it to pass through clearance 18 between the seat and the top of the bowl, a substantially vertical tract 51, bent downwardly from the outer end of horizontal tract 50 so as to reach a point somewhat below the level of the lower surface 52 of rim 12, and a substantially horizontal tract 53 bent underneath the rim and then extending close to the side surface of the bowl as shown in dotted lines at 53', in Fig. 1.

75 The device is normally inoperative and in this condition supporting member 32 is in the angular position in which the delivery arm occupies the position shown in dotted lines at 53' in Fig. 1.

80 When from this position the supporting member is moved by means of handle 33 to the position shown in full lines in Fig. 1, nozzle 45 carried by tract 53 comes to occupy a position within the bowl in which its axis remains on a vertical longitudinal plane passing through the center of the bowl and is up-

70

130

wardly inclined towards the rear of the bowl.

Fluid under pressure issuing from the nozzle will therefore be projected in an upwardly inclined direction towards the rear of the bowl. More particularly the direction of the fluid jet issuing from the nozzle will be so arranged that the fluid under pressure will strike directly against the body outlet of the occupant of the seat in connection with which the cleansing operation is to be performed.

The nozzle proper is preferably screwed onto the outer end of tract 53, the axis of said outer end being preferably directed at right angles to the central longitudinal plane of the bowl when the fluid delivery arm 44 is moved to its operative position, shown in full lines in Fig. 1. The nozzle tract can therefore be elbow-shaped and can have its tip end at right angles to the ends of its attaching end.

A typical construction of nozzle designed along these lines is shown in Fig. 8, in which the outer end 46' of tubular member 46 is threaded as shown at 54, and projects beyond the outer end 47' of tubular member 47 which is also threaded as shown at 55. The nozzle proper comprises an outer shell 56 bent at a 90° angle forming an internally threaded sleeve portion 57 which may be screwed upon the outer end 47', and a tip end 58 directed at right angles thereto, said tip end being preferably inwardly tapering towards the nozzle outlet 59. Said nozzle furthermore, comprises an inner tubular portion 60 which is also bent at a 90° angle forming an internally threaded sleeve portion 61 which may be screwed onto end 46' and a tip portion 62 coaxial with tip portion 58 forming therewith an annular passage 63.

It will be seen that by virtue of this arrangement, the inclination of the axis of the tip end of the nozzle with respect to a longitudinal vertical plane passing through said axis and through the center of the closet bowl can be adjusted at will, the nozzle being retained in its adjusted position by means of a check nut 64.

The tip end 58 of the nozzle is preferably provided with an inwardly flaring sleeve 65 forming therewith an annular passage 66 through which air may be drawn by the suction created through said passage by the jet of fluid under pressure issuing through outlet 59. Air is supplied to chamber 25 within stand 19 by a pump actuated by the water available from the water supply. In the preferred embodiment of our invention, we use in connection with stand 19 and head 21 a controlling valve 67 by means of which the supply of water to the nozzle or to the pump and the supply of air from the pump to the nozzle can be selectively controlled.

Said valve is so designed that in its inoperative position, no flow of either water or air takes place. By moving said valve one step

forward the water from the supply system will be directed to chamber 23 through pipe 24, so that a cleansing spray will issue from nozzle 45. By moving the valve to its next step, the water from the water supply will be directed to the hydraulically operated pump, and the air under pressure delivered by said pump will be directed by the valve through pipe 68 to air chamber 25 and will reach outer passage 48 of the fluid delivery arm ultimately issuing through nozzle 45 in the form of a jet of air under pressure.

The controlling valve is shown in Figs. 1 and 2, and is also illustrated in detail in Figs. 6 and 7. From said figures it will be seen that the valve comprises a body 69 mounted on head 21, said body being provided with various ports of which 70 is a port for the admission of water from the water supply through pipe 71, controlled by a valve 72; 73 is a port for the discharge of said water through pipe 24 leading to water chamber 23 in the stand; 74 is a port leading the water to the air pump through a pipe 75; 76 is a port leading the air under pressure from the air pump to the valve through a pipe 77; and 78 is a port leading the air from the valve to the air chamber 25 through pipe 68.

The valve also comprises an angularly movable member or cock 79 provided with tubular passages 81, 82 adapted to establish the various connections between the ports mentioned required by the operation of the device. Said cock is provided with an operating handle 80 which is shown in Figs. 6, 7 in its first operative position marked #2 in Fig. 6, the normal or inoperative position of said handle being marked #1 at the left hand in Fig. 6 and the second operative step of the same being marked #3 at the right in the same figure.

In the position shown, water from the supply system is directed to chamber 23 in the stand for the cleansing operation, and therefore passage 81 of cock 79 establishes connection between ports 70 and 73, while the other ports are disconnected from one another.

After the cleansing operation has been completed, handle 80 is moved to the next position 3 where passage 81 of the cock will establish communication between ports 70 and 74 and passage 82 will establish communication between ports 76 and 78.

In this position therefore, the water from the water supply will be directed to the pump, and the air discharged by the pump will be delivered through pipe 68, to air chamber 25 and will issue from the nozzle 45 in the form of a jet of air under a suitable pressure, said pressure being preferably sufficient as stated, to blow off liquid particles adhering to the wet surface so as to increase the efficiency of the drying action.

The air thus delivered, as stated, is preferably heated by any suitable means, for instance, by means of the heating element 28 which may be energized at the proper time. 5 The water also is preferably heated and this may be done in various ways for instance, by admitting to chamber 23 some water from the hot water pipes by means of a suitable valve (not shown). In the arrangement illustrated, 10 the water may be warmed up by the heat given off by the heating element 28, and therefore said heating element may be energized not only when the air is flowing through passage 27 but also before when 15 water is flowing through chamber 23 so as to issue from the nozzle in the form of a cleansing jet.

We have therefore, illustrated an arrangement whereby the igniting element will be 20 energized as soon as the fluid delivery arm is moved to operative position by the angular displacement of supporting member 32. As Fig. 3 clearly shows, the heating element 28 is provided with two terminals 83, 84, one of 25 said terminals being connected to a line wire 85 and the other one being connected by means of a wire 86 to one of the terminals 87 of a switch 88. Said switch has another terminal 89 to which is connected the other 30 line wire 90.

From said switch terminals 87, 89 respectively, project two contact clips 91, 92 having their tip ends opposite to but spaced from each other. Supporting member 32 carries 35 at its lower end, a contact finger 93 which closes the circuit between clips 91, 92 when supporting member 32 is moved to its operative position shown in Fig. 3, said contact finger again interrupting the circuit when 40 said supporting member is moved to its normal or inoperative position. It is therefore obvious that heating element 28 will be energized as soon as the fluid delivery arm is set in its operative position, raising the temperature of the water contained in chamber 23.

The water used in the pump to compress the air may be discharged in the sewer by means of a pipe 94 which may for this purpose be connected to the discharge end of 50 the siphon of the closet bowl, or to the discharge pipe thereof.

The water available from city supply systems is generally at a fairly high pressure so that its energy can readily be used to pump 55 and compress air at relatively low pressures required for the drying operation.

For the sake of example, in the drawings we illustrate a type of air pump which may be conveniently used in our apparatus, in 60 which the water acts as a liquid piston directly creating the suction and the discharge of the air to and from the pump chambers.

Said air pump comprises two pumping chambers 95, 96, arranged side by side through which runs a shaft 97 carrying at

one end a lever 98. Chamber 95 is provided at its lower end with a passage 99, and chamber 96 with a similar passage 100, said passages alternately acting as inlet and outlet for the water admitted to or discharged from each chamber. A valve body 101 is fixed to the underside of chamber 95 in correspondence of passage 99 and a similar valve body 102 is fixed to the underside of chamber 96 in correspondence of passage 100, said two 75 valve bodies being in coaxial alignment with each other. Valve body 101 is provided with a port 103 registering with passage 99, a port 104 connected to water supply pipe 75 by a tubular connection 105 and a port 106 connected to the water discharge pipe 94 by a tubular connection 107. In a similar manner valve body 102 is provided with a port 108 registering with passage 100, a port 109 connected to the water supply pipe 75 by a 80 tubular connection 110 and a port 111 connected to the water discharge pipe 94 by a tubular connection 112.

Within valve body 101 is rotatably mounted a cock member 113, and within valve body 102 is rotatably mounted a similar cock member 114, said cock members being both fixed on the same shaft 115 for simultaneous operation. Shaft 115 has a portion projecting beyond valve body 102 carrying a lever 116 which is mounted substantially at the same angle as lever 98 and is connected therewith by a connection 117.

The two valve cocks are so arranged that when water is admitted to one of the pump chambers water is discharged from the other, and vice versa. In the position shown water is admitted to chamber 95 through a passage 118, in cock 113, said passage connecting port 103 to port 104. At the same time water is discharged from chamber 96 through a passage 119, provided in cock 114, said passage connecting port 108 to port 111. If shaft 115 is angularly displaced about 45° in a 105 counterclockwise direction from the position shown the conditions will be reversed, inasmuch as water will then be discharged from chamber 95 through a passage 120 provided in cock 113, said passage establishing communication between port 103 and port 106, and water will be admitted to chamber 96 through a passage 121 provided in cock 114, 110 said passage establishing communication between port 108 and port 109.

Chamber 95 is provided at the top with an air inlet 122 equipped with a valve 123, which will admit air within chamber 95 when a suction is created within said chamber. Said chamber is also equipped with an air delivery outlet 124 through which air will be expelled from chamber 95 when water is admitted to said chamber, said outlet being controlled by a valve 125.

In a similar manner, chamber 96 is provided with an air inlet 126 controlled by a valve 130

127 and an air outlet 128 controlled by a valve 129. The two air outlets 124, 128 are joined by a common fitting 130, to pipe 77 delivering the air from the pump to valve 67. On the portion of shaft 97 running through chamber 95, is fixed a lever 131, carrying at its outer end a float 132, said lever being in its depressed position when water is being admitted to chamber 95 as shown. The hub 10 portion of lever 131 is formed with a lug or projection 133 against which abuts the tip end 134 of a stop lever 135 pivotally mounted at 136, said stop lever being equipped with a depending float 137, carried by a rod 138 vertically shiftable between two guide pins 139, 140.

In a similar manner, the portion of shaft 97 running across chamber 96 is provided with another lever 141 carrying at its outer end a 20 float 142, the hub portion of said lever being provided with a lug or projection 143 against which may abut the tip end 144 of a stop lever 145 pivotally mounted at 146, when lever 141 is in its downward position. Like in the 25 previous case, stop lever 145 is equipped with a float 147 carried by a rod 148 vertically slidable between guide pins 149, 150. Lever 141 is angularly displaced in a clockwise direction from lever 131, so that when lever 131 occupies its downward position, lever 141 occupies its recessed position to the left as shown in Fig. 5. In this position, of shaft 97, rotation of said shaft in a counterclockwise direction is prevented by lever 135 having 30 its tip end 134 engaging lug or projection 133, so that float 132 will not be able to rise as the water admitted through passage 99 gradually fills up chamber 95. For the same reason float 142 will not be able to descend 35 while the water contained in chamber 96 is being discharged through passage 100.

While water is being admitted to chamber 95 the air contained within said chamber is expelled through outlet 124 and pipe 77, said 40 air ultimately reaching nozzle 45 as explained, since when water is admitted to the pumping chambers, the cock of valve 69 is in the position 3 of Fig. 6. In a similar manner as water is being discharged from chamber 96 air will 45 be admitted to said chamber through air inlet 126.

When the water in chamber 95 reaches a level sufficient to raise float 138, this will cause lever 135 to become disengaged from lug or projection 133, and float 138 will then be free to instantly ascend causing angular movement of shaft 97 in a counterclockwise direction. This angular movement will be shared by lever 98 which will transmit it to lever 116 50 through connection 117 reversing the valve connections established by cocks 113, 144. At the same time, float 142 will descend to the position where lug or projection 143 will be engaged by the tip end 144 of lever 145. 55 Water will now be discharged from chamber

95 through the newly established connection between port 103 and port 106, and water will be admitted to chamber 96 through the newly established connection between port 108 and 109. Consequently the air will be discharged from chamber 96 continuing the flow of air to the nozzle through pipe 77. 70

By virtue of this arrangement the operation of the pump is entirely automatic, starting as soon as lever 80 of valve 69 is moved 75 to position 3 and stopping as soon as said lever is moved back to position 1.

The flow of water may be stopped by means of valve 72 when lever 80 is moved back to position 1 in order to prevent water from issuing once more through the nozzle, while said lever reaches position 2 on its way to position 1, or else the ports in valve 69 and the passages in cock 79 may be so arranged that the valve is in its inoperative position 80 when the lever occupies the intermediate position 2 shown in Fig. 6, being moved to one side or the other of said position, in order to supply water or air to the nozzle, as will be understood. 90

From the foregoing, it will be seen that we provide a novel and convenient arrangement whereby the necessity of using an electric motor and a power operated air pump is entirely done away with. 95

Our invention may be carried into practice in ways different from those shown without departing from the inventive idea; the drawings will therefore be understood as being intended for illustrative purposes only and not 100 in a limiting sense. Accordingly, we reserve the right to carry our invention into practice in all those ways and manners which may enter, fairly, into the scope of the appended 105 claims.

We claim:

1. In apparatus of the class described, the combination with a bowl adapted to support a human body in a sitting posture, means for delivering air within said bowl against an 110 exposed portion of the body of the occupant of the bowl, and a source of water supply, of an air pump actuated by the water available from said source of supply, for supplying air under pressure to said air delivering 115 means.

2. In apparatus of the class described, the combination with a bowl adapted to support a human body in a sitting posture, means for selectively delivering a jet of water or a jet of air within said bowl against an exposed portion of the body of the occupant of the bowl, and a source of water supply, of an air pump adapted to be actuated by the water available from said source of supply, for supplying air under pressure to said delivering 120 means, and means for selectively connecting said source of water supply to said pump or to said delivering means. 125

3. In apparatus of the class described, for 130

use in connection with a bowl adapted to support a human body in a sitting posture, and a source of water supply, means for selectively delivering a jet of water or a jet of air within said bowl against the body of the occupant thereof, an air pump adapted to be actuated by the water available from said source of supply, for supplying air under pressure to said air chamber, and means, mounted on said stand, for selectively connecting said source of supply to said pump or to said water chamber, said connecting means also controlling the delivery of air supplied by said pump, to said air chamber.

5 10 15 20 25 30

use in connection with a bowl adapted to support a human body in a sitting posture, and a source of water supply, means for selectively delivering a jet of water or a jet of air within said bowl against the body of the occupant thereof, an air pump adapted to be actuated by the water available from said source of supply, for supplying air under pressure to said delivering means, and a multiple way valve for selectively connecting said source of water supply to said pump or to said delivering means, said valve also controlling the delivery of air supplied by said pump, to said delivering means.

4. In apparatus of the class described, for use in connection with a bowl adapted to support a human body in a sitting posture, and a source of water supply, means for selectively delivering a jet of water or a jet of air within said bowl against the body of the occupant thereof, an air pump of the liquid piston type, adapted to be operated by the water available from said source of supply, for supplying air under pressure to said delivering means, and a multiple way valve for selectively connecting said source of water supply to said pump or to said delivering means, said valve also controlling the delivery of air supplied by said pump, to said delivering means.

15 20 25 30 35 40

5. In apparatus of the class described, the combination with a bowl adapted to support a human body in a sitting posture, means for delivering air within said bowl against an exposed portion of the body of the occupant of the bowl, and a source of water supply, of an air pump actuated by the water available from said source of supply, for supplying air under pressure to said air delivering means, and means for heating the air thus supplied.

6. In apparatus of the class described, the combination with a bowl adapted to support a human body in a sitting posture, means for selectively delivering a jet of water or a jet of air within said bowl against an exposed portion of the body of the occupant of the bowl, and a source of water supply, of an air pump adapted to be actuated by the water available from said source of supply, for supplying air under pressure to said delivering means, means for selectively connecting said source of water supply to said pump or to said delivering means, and electric means for heating the water and air thus supplied to said delivering means.

7. In apparatus of the class described, for use in connection with a bowl adapted to support a human body in a sitting posture, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump adapted to be actuated by the water available from said

bers and said delivering means, an air pump adapted to be actuated by the water available from said source of supply, for supplying air under pressure to said air chamber, and means, mounted on said stand, for selectively connecting said source of water supply to said pump or to said water chamber, said connecting means also controlling the delivery of air supplied by said pump, to said air chamber.

75 80 85 90 95

8. In apparatus of the class described, for use in connection with a bowl adapted to support a human body in a sitting posture, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump adapted to be actuated by the water available from said source of supply, for supplying air under pressure to said air chamber, and a multiple way valve, mounted on said stand, for selectively connecting said source of water supply to said pump or to said water chamber, said valve also controlling the delivery of air supplied by said pump, to said air chamber.

9. In apparatus of the class described, for use in connection with a bowl adapted to support a human body in a sitting posture, a sewer discharge for said bowl, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump adapted to be actuated by the water available from said source of supply, for supplying air under pressure to said air chamber, means, mounted on said stand, for selectively connecting said source of water supply to said pump or to said water chamber, said connecting means also controlling the delivery of air supplied by said pump, to said air chamber, and means for leading to said sewer discharge, the water exhausted from said pump.

100 105 110 115 120

10. In apparatus of the class described, for use in connection with a bowl adapted to support a human body in a sitting posture, a sewer discharge for said bowl, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump adapted to be actuated by the water available from said

source of supply, for supplying air under pressure to said air chamber, a multiple way valve, mounted on said stand, for selectively connecting said source of water supply to said pump or to said water chamber, said valve also controlling the delivery of air supplied by said pump, to said air chamber, and means for leading to said sewer discharge, the water exhausted from said pump.

11. In apparatus of the class described, for use in connection with a bowl adapted to support a human body in a sitting posture, a sewer discharge for said bowl, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump of the liquid piston type, adapted to be operated by the water available from said source of supply, for supplying air under pressure to said air chamber, a multiple way valve, mounted on said stand, for selectively connecting said source of water supply to said pump or to said water chamber, said valve also controlling the delivery of air supplied by said pump, to said air chamber, and means for leading to said sewer discharge, the water exhausted from said pump.

12. In apparatus of the class described, for use in connection with a bowl adapted to support a human body in a sitting posture, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump adapted to be actuated by the water available from said source of supply, for supplying air under pressure to said air chamber, a multiple way valve, mounted on said stand, for selectively connecting said source of water supply to said pump or to said water chamber, said valve also controlling the delivery of air supplied by said pump, to said air chamber, and means for heating the air supplied to said air chamber.

13. In apparatus of the class described, for use in connection with a bowl adapted to support a human body in a sitting posture, and a source of water supply, a stand, a head rotatably mounted on said stand, means carried by said head for selectively delivering a jet of water or a jet of air within said bowl against the body of the occupant thereof, a water chamber and an air chamber within said stand, connections between said chambers and said delivering means, an air pump adapted to be actuated by the water avail-

able from said source of supply, for supplying air under pressure to said air chamber, a multiple way valve, mounted on said stand, for selectively connecting said source of water supply to said pump or to said water chamber, said valve also controlling the delivery of air supplied by said pump, to said air chamber, and electric means, controlled by said rotatable head, for heating the air supplied to said air chamber.

FERRUCCIO GUIDETTI.
